United States Patent Office

Des. 188,135
Patented June 7, 1960

188,135

BOX OR SIMILAR ARTICLE

Melvin Koenig, 41 Shore Drive N., Miami, Fla.

Filed Apr. 2, 1959, Ser. No. 55,316

Term of patent 14 years

(Cl. D58—11)

Fig. 1 is a front elevational view of a box showing my new design;

Fig. 2 is a top plan view thereof; and

Fig. 3 is a rear elevational view thereof.

I claim:

The ornamental design for a box or similar article, substantially as shown and described.
